US00D667020S

(12) **United States Design Patent**
MacKenzie et al.

(10) **Patent No.:** US D667,020 S
(45) **Date of Patent:** ** Sep. 11, 2012

(54) **DISPLAY SCREEN WITH GRAPHICAL USER INTERFACE**

(75) Inventors: **Stephen James MacKenzie**, Ottawa (CA); **Ian Shaw**, Ottawa (CA)

(73) Assignee: **Research In Motion Limited**, Waterloo, Ontario (CA)

(**) Term: **14 Years**

(21) Appl. No.: **29/375,611**

(22) Filed: **Sep. 24, 2010**

(51) LOC (9) Cl. **32-00**

(52) U.S. Cl. **D14/486**

(58) Field of Classification Search **D14/485-495; 715/700-867**

See application file for complete search history.
